UNITED STATES PATENT OFFICE.

FERDINAND MESSMER, OF ST. LOUIS, MISSOURI.

AUTOMATIC VENT.

SPECIFICATION forming part of Letters Patent No. 253,306, dated February 7, 1882.

Application filed November 8, 1881. (No model.)

To all whom it may concern:

Be it known that I, FERDINAND MESSMER, of St. Louis, State of Missouri, have invented a new and useful Automatic Vent, of which the following is a specification.

My invention relates to improvements in automatic vents to be applied to vessels, barrels, or kegs in which liquor, beer, &c., is kept, in order to better draw, tap, or discharge the fluid. The objects of my improvements are to obtain decisive, reliable, and perfect automatic action on the part of the vent or valve—that is to say, to be reliable in its automatic opening action to let air inside the keg as the fluid is drawn off, and in similar manner to be reliable in its self-closing action to shut out the external air; also to accomplish the said actions without leakage and without noise. I attain these objects by the vent illustrated in the accompanying drawings, in which—

Figure 1 shows my improved vent when applied and used for a beer-keg in connection with a faucet. Fig. 2 is a side elevation of the vent and its tubular stem. Fig. 3 is an edge view of Fig. 2. Fig. 4 is the same view when vent is inflated. Fig. 5 is a vertical section on line $x'x'$ of Fig. 3. Fig. 6 is a section on line $x'x'$ of Fig. 2 when vent is closed or not inflated. Fig. 7 is a section of Fig. 4 when inflated condition; and Figs. 8 and 9 are respective end views, the former showing the mouth of vent closed, the latter view showing mouth open. The respective figures 2, 3, 4, 5, 6, 7, 8, 9 are here illustrated enlarged (to what in practice the vent is made) in order to better show and explain the construction and operation of the parts. Fig. 10 is a cross-section of the vent, taken on line x^2x^2 .

Similar letters refer to similar parts throughout the several views.

A is the tubular stem, forming part of which is the vent B. The entire stem and vent being of flexible material—such as rubber—is made (by pressure and molds employed) to be of the constructive shape and have the structural features, as follows: The vent is a tube flattened out so that its two opposite sides, b b , come together, which closes the vent, (see Figs. 2, 3, 6, 8;) vice versa, when by inflation or air-pressure the said walls or sides are made to part the mouth of the vent at b' is open to permit the

escape of the air through the vent. (See Figs. 4, 7, 9.) The opposite edges, b^2 b^2 , of the vent I curve in outline, as shown in Figs. 2 and 5, in order that the wider portion shall exist centrally across the vent on line x^2x^2 . (See Figs. 2 and 5.) The curved edges b^2 b^2 give more spring to the walls of the mouth of the vent, facilitating its proper opening and closing action, and, together with the increased area existing cross-wise of the sides, gives sufficient weakness to the said midway portion of the sides to enable the vent proper to open and close more easily in the middle portion thereof; also a greater volume of air can be forced in the middle part of the vent (where it is the widest) to swell the same and facilitate the opening of the walls of the mouth at b' . Further, the curved edges b^2 b^2 (where they unite with or form part of the sides b b) I make thinner, leaving the center portion of the sides thicker. Thus the external appearance of the vent taken on line x^2x^2 (or viewed at the end of the mouth b') is oval-shaped, as shown in Figs. 8 and 9. By so making the edges thinner and the center portion thicker the vent can the better expand and contract in its center portion in accordance with the pressure, and said air-pressure can the more easily open or close the mouth of the vent. The thicker portion of the vent prevents that rapid vibration which produces noise and is so disagreeable, specially when the air-pressure is strong. The stem A extends into the body of the vent, and said extended portion a , I shape tapering to the center point of the vent. (See Figs. 2, 3, 4, 5, 6.) By this means the air pressure or current has free passage to near the outer extremity or mouth of the vent.

As stated, the closed condition of the vent is as shown in Figs. 3, 6, and 8—that is, the flattened sides b b are in contact with each other, which closes the mouth of the vent and prevents the return of any air or gas from the keg and leakage through the vent. When the air-pressure or inflation takes place the air-current with all its force strikes the center of the vent, causing its flattened sides to swell or bulge, and in so doing opens a passage-way which permits the air-current to escape into the keg above the fluid it contains. As soon as the inflation ceases the sides b b of the vent spring back or contract, first in the middle part

of the vent proper, which action draws the walls of the mouth b' together and the vent is closed. Thus the vent automatically closes its mouth b' when there is no inflation, and automatically opens its said mouth when the vent is inflated.

In Fig. 1 I have illustrated the vent as forming part of hose of different diameters and sections, the latter being in connection with a faucet. When so applied and used the hose assumes nearly a perpendicular position within the keg, the vent proper floating on top of the liquid. The vent can also be applied to the bung or vent-cock as a pendant therefrom.

I do not desire to limit myself to the use of rubber as the only material to make the said automatic vent; hence

What I claim is—

The automatic vent herein described, consisting of two united flat sides whose opposite edges are curved, said sides being wider cross-wise on a line midway of their length, the mouth as well as any cross-section of said sides being oval in shape with its said curved edges made thinner than the longitudinal central portion of said sides, and the taper end of a tubular stem extending into the body and up to the center and widest portion of the vent proper, substantially as and for the purposes set forth.

In testimony of said invention I have hereunto set my hand.

FERDINAND MESSMER.
